UNITED STATES PATENT OFFICE.

HENRY M. QUACKENBUSH, OF HERKIMER, NEW YORK.

AIR-GUN.

SPECIFICATION forming part of Letters Patent No. 244,484, dated July 19, 1881.

Application filed May 6, 1881. (No model.)

To all whom it may concern:

Be it known that I, HENRY M. QUACKENBUSH, a citizen of the United States, residing at Herkimer, in the county of Herkimer and State of New York, have invented certain new and useful Improvements in Air-Guns; and I do hereby declare the following to be a full, clear, and exact description of the invention, such as will enable others skilled in the art to 5 which it appertains to make and use the same, reference being had to the accompanying drawings, and to letters or figures of reference marked thereon, which form a part of this specification.

15 This invention relates to air-guns in which a spring-impelled piston drives the air from the chamber of a receiver against a projectile within the tube or barrel.

It consists partly in the combination of an 20 inclosing-sleeve with the barrel, the sleeve having a longitudinal motion in the receiver, and the tube or barrel being immovable in the latter.

It also consists in the peculiar construction 25 of the trigger-guard and said sleeve, whereby said guard limits the outward motion of said sleeve and prevents it from turning; also in providing said guard with an eye or bend for grasping near its front end.

30 It also consists in other improvements in construction and combination hereinafter set forth and claimed.

The drawings accompanying this specification represent in Figure 1 a vertical longitudinal section of a gun containing my improvement, and in Fig. 2 a plan, while Fig. 3 is a cross-section of the same, taken on the line *a-b* of Fig. 1, and Fig. 4 a like section, taken on line *c-d* of said Fig. 1. Fig. 5 is a longitudinal 40 section of a modified construction of the gun.

In these drawings, *A* represents the frame or "receiver," as it is usually termed, of the arm, which is a straight cylinder of metal with an axial bore, or chamber *A'*, of uniform diameter, and containing in such bore a loosely-fitting piston, *B*, which is impelled forward by a coiled spring, *C*, placed between its rear end and the rear closed end of the cylinder.

45 *D* is the stock of the gun, *E* the trigger, and *F* the sear of the lock, the said sear operating to arrest or discharge the piston in a manner common to many guns of this class.

In carrying out my improvement I proceed as follows: I employ a tube or sleeve, *G*, having a straight bore of uniform diameter, and I 55 dispose the rear end of this sleeve within the front end of the chamber *A'*, in which it is adapted to slide with an air-tight joint, or practically so, the bore of the receiver constituting the support of the sleeve.

60 The barrel proper is shown at *J* as a straight tube of uniform diameter, this tube having a bore, *a*, of uniform diameter except a contraction at one point, as hereinafter explained, and being deposited within the bore of the sleeve *G*, which constitutes a support for it, the said barrel *J* being prevented from rotation within the sleeve and with respect to the receiver by a screw-plug, *h*, to be hereinafter explained. The sleeve *G* is adapted to slide longitudinally 65 within the chamber *A'* and act to depress the piston and its spring, and cock such piston, and when at its extreme forward position serves to close the mouth of the chamber *A'* and prevent escape of air thereat. The bore of the 70 tube *J* is contracted at its rear end, as shown at *c*, this contraction or throat, as before stated, serving to swage the projectiles and reduce them to a common diameter before entering the remainder of said bore, thereby reducing 75 the friction in the latter.

80 The yielding stop-pin before alluded to is shown at *d* as having a straight shank, *e*, which extends through orifice *f* in the top of the barrel, and an opening, *g*, in the lower end of a 85 screw-plug, *h*, which is screwed into the top of the receiver, this plug having a pocket, *i*, which contains the head of the stop-pin, and a spiral spring, *j*, which crowds such pin toward the barrel, the stress of such spring being governed by a screw, *k*, screwed into the mouth of the pocket *i*. The point or nose of the stop-pin *d* protrudes slightly into the bore of the tube or barrel *J*, to prevent the shot from sliding out when the gun is pointed downward, and to offer a weak or yielding impediment to the projectile after the latter has been crowded through the throat *c* into the bore of the barrel, as shown in Fig. 1 of the drawings, and when the piston is released and driven forward by the stress of its spring this pin yields to the pressure upon the projectile by the current of air from behind, and permits of escape of 90 such projectile.

The guard before alluded to is shown at L as a rod of spring metal inserted at its rear end in a socket in the receiver, and securely fastened therein and extending in a line beneath 5 the trigger, and thence alongside the receiver and to the front end of the latter, where it terminates in a reverse bend, by which is formed an eye or hook, l, in which a person's finger or thumb may be inserted, and a straight spur 10 or stop, m, parallel with the main portion and with the bore of the sleeve G, this stop portion m being disposed within a channel, n, in the under side of the said sleeve, and abutting at its rear end (when the sleeve is in its extreme outward position) against the rear boundary or abutment o of said channel. The spur or stop m serves to prevent rotation of the sleeve G. The longitudinal elasticity of the guard L relieves, as before stated, the rear end 20 of the sleeve G from the thrusts of the piston as the arm is discharged, while its lateral elasticity permits the stop m to be removed from the channel n when it is desired to remove the two parts of the barrel or the same and the 25 piston and its spring.

To permit of removal of the tube J the screw-plug h is raised from out the opening f in the top of the barrel, while to permit of removal of the sleeve G, or the same and the piston 30 and its spring, the user's thumb or finger is inserted in the hook l, and the spur m removed from the channel n.

To crowd the projectile through the throat e in the act of loading the arm I secure with 35 in the rear end of the bore of the sleeve G a blade or follower, p, which is disposed in alignment with the bore of the barrel J, a passage, q, remaining about this blade to permit of passage of air from the piston-chamber N of the 40 receiver.

The rear part of the slot l in the sleeve G constitutes the opening through which the projectile is inserted into the end of the barrel J, and a coinciding opening, r, is created in the 45 upper front part of the receiver for the same purpose. The slot l does not extend to the rear end of the sleeve G. The unslotted rear portion, t, of the latter closes the front end of chamber A', so that no air can pass from said 50 chamber when the piece is fired except such as is driven through said sleeve into the rear end of barrel J.

To aid in lessening the force of the impact of the piston and frame I add to the front end 55 of such piston a pad, c', of leather, rubber, or other elastic or semi-elastic material, as shown in the accompanying drawings. This pad is inserted in a pocket in the front end of the piston; but it may be secured to the latter by 60 other means.

To load this arm, place the muzzle of the barrel upon the floor or solid abutment, with the palm of the right hand in the hollow of the butt, and then press down upon the butt 65 until the sleeve G is thrust backward to such an extent as to drive the piston B into its chamber and set or cock it in rear of the sear

F. The projectile, whether a spherical or other solid slug, or a dart, is now inserted, by hand, in the rear end of the inner tube or barrel, J, 70 and lastly, the sleeve is pulled forward by the user to its extreme position, thereby closing the opening r in the receiver, while at the same time the advance of the follower p crowds the projectile through the throat c into the bore of 75 the barrel beyond where it is arrested by the stop-pin d. After sighting the arm the trigger is pulled and the piston released and shot forward by its spring, thereby driving a column of air through the chamber A' and the 80 bore of the barrel J and expelling the projectile from the latter.

My Patent No. 178,327 shows a barrel made in one piece and sliding longitudinally in the receiver for the same purposes as the longitudinal movement of sleeve G. There are some decided advantages, however, in constructing the sleeve and tube separately—one is that I am enabled to have both my sights stationary. When the barrel slides it becomes worn, and 90 the forward sight, of course, is in some danger of getting out of an exact line with the rear sight. Again, the construction above described enables me to use the fastenings m n o without grooving or weakening the tube J or 95 barrel proper; also, when the sleeve G is worn it can be withdrawn and another substituted, tube J still remaining serviceable. Finally, the sleeve G will brace and shield the barrel, and may have other advantages not herein 100 enumerated.

A modification of my gun is shown in Fig. 5 of the drawings, the modified construction relating to the method of introducing the projectile (which is a spherical bullet) into the 105 end of the barrel and discharging it from the latter. In this modification the construction of the gun is the same as before described, with the following exceptions: In lieu of inserting the projectile directly into the end of 110 the barrel by hand and then crowding it through the throat of the barrel by the return or forward movement of the sleeve, and finally discharging it from the barrel by the current of air through the latter, as before explained, I 115 omit the said sleeve altogether and employ a single barrel, B', which is contained at its rear end within the front end of the receiver and is adapted to slide longitudinally therein, and has a vertical passage, u, created in its upper 120 rear part to permit a bullet to be inserted into its bore a, this passage u being situated immediately in rear of the throat c. The piston has affixed to its front end a rigid discharging-rod, v, disposed in alignment with the axis of 125 the chamber A' and the bore of the barrel, the front end of this rod v, when the piston is set or cocked and the barrel is at its forward or firing position, remaining immediately in rear of the rear end of the barrel. An opening, w, 130 is created in the top of the receiver A and communicates with the rear end of the chamber A', and is so situated that when the barrel B is pushed rearward to its fullest extent within

the said chamber in the act of cocking the piston, the passage *w* coincides with the passage *u* of the barrel and permits a bullet to be dropped into the latter, and so as to rest upon the rear end of the discharging-rod *v*, the greater part of such rod at this time being inclosed by the bore of the barrel, as shown in dotted lines in Fig. 5 of the drawings.

The operation of this modified form is as follows: To prepare the arm for loading, the barrel is pushed rearward (by any suitable means) until the piston passes beyond the sear *F* and is cocked, at which time the two passages *u w* coincide. A bullet is now dropped into the passage *u* upon the top of the rod *v* and the barrel pulled forward to its extreme position, the bullet meanwhile rolling along the rod *v* until, as the barrel completes its outward movement, such bullet passes beyond the rod and drops from the front end of such rod into the rear end of the bore of the barrel immediately in rear of the throat *c*. Upon the trigger being pulled and the piston and its rod *v* shot forward, the rod in its passage drives the bullet (shown at *x* in said Fig. 5 of the drawings) through the throat, and in conjunction with a current of air discharges it from the barrel, the bullet in its passage through the throat being swaged to a given diameter, in manner and for the purpose as hereinbefore explained.

In this modification the guard *L* acts as a yielding or elastic recoil-seat to the barrel, and its stop *m* enters a groove, *y*, in the under side of the barrel *B'*, the rear boundary, *z*, of this abutment bringing up against such stop when the barrel is in its firing position.

I claim—

1. In combination with barrel *J* and receiver *A*, the sliding sleeve *G*, surrounding said barrel and filling the end of chamber *A* to compel all the air driven from said chamber in the act of firing to pass through said sleeve and barrel.
2. The combination of sleeve *G* with tube or barrel *J*, which it surrounds, and tubular receiver *A*, which surrounds the rear end of said sleeve, the barrel being immovable with respect to the receiver, and the sleeve adapted to slide longitudinally with respect to said tube and receiver.
3. In combination with receiver *A*, piston *B*, and sleeve *G*, sliding within said receiver, and having a rear opening or passage, *q*, a barrel

or tube, *J*, having a tapered throat, *c*, in its bore, near the rear end thereof, and a blade, *p*, which protrudes from said passage *q* into said barrel, substantially as set forth.

4. The stop-pin *d*, spring *g*, and recessed screw *h*, in combination with receiver *A*, piston *B*, sleeve *G* within said receiver, and tube *J* within said sleeve, substantially as set forth.

5. In combination with the tubular receiver and the piston, the tube *J*, with its throat or contraction *c*, and the sleeve *G*, with its follower *p*, the tube being immovable with respect to the barrel, and the sleeve encompassing and sliding upon the tube and closing the mouth of the receiver, as and for purposes explained.

6. The elastic guard *L*, bent to form a stop for sleeve *G*, in combination with said sleeve, and a shoulder or stop thereon, receiver *A*, and spring-impelled piston *B*, substantially as and for the purpose set forth.

7. The guard *L*, in combination with stock *D*, to which it is attached, receiver *A*, and sleeve *G*, longitudinally recessed or grooved on its under side, the forward end of said guard having a straight piece, *m*, which sets into said longitudinal recess to prevent the rotation of said sleeve.

8. The guard *L* bent to form a loop or eye, *l*, and a terminal piece, *m*, in combination with longitudinally-grooved sleeve *G*, substantially as set forth.

9. The elastic guard *L*, having straight part *m*, in combination with receiver *A*, stock *D*, and sleeve *G*, the latter having groove *n* and stop or shoulder *o*, substantially as set forth.

10. In an air-gun, the combination of a barrel having a taper throat or chamber with a swaging follower, the longitudinal movement of one of said parts causing said follower to force the bullet through said throat, for the purpose set forth.

11. In combination with a receiver and a barrel, the sleeve *G*, around said barrel but within said receiver, and the blade *p*, which sets within the rear passage, *q*, of said sleeve, leaving space on each side of said blade for air to be driven through said passage.

I testimony whereof I affix my signature in presence of two witnesses.

HENRY M. QUACKENBUSH.
